UNITED STATES PATENT OFFICE.

JOHN M. HANSEN, OF BELLEVUE, PENNSYLVANIA, ASSIGNOR TO THE
PRESSED STEEL CAR COMPANY, OF PITTSBURG, PENNSYLVANIA.

DESIGN FOR AN END SILL FOR CARS.

SPECIFICATION forming part of Design No. 32,543, dated April 17, 1900.

Application filed March 17, 1900. Serial No. 9,118. Term of patent 14 years.

To all whom it may concern:

Be it known that I, JOHN M. HANSEN, a citizen of the United States, residing at Bellevue, in the county of Allegheny and State of Pennsylvania, have invented and produced a certain new and original Design for Metallic End Sills for Railway-Cars, of which the following is a full, clear, and exact description.

This invention relates to what are known as "end sills," and especially end sills for freight-cars, and specifically to metallic end sills.

In the accompanying drawings, illustrating my invention, in the several figures of which like parts are similarly designated, Figure 1 is a perspective view. Fig. 2 is a top plan view. Fig. 3 is a front or end elevation. Fig. 4 is a central vertical cross-section on an enlarged scale.

As shown in the drawings, the leading or material features of my design consist of an integral end sill having a flat face *a* next the draw-bar opening *b*, contiguous tapered or inclined sides *c*, top and bottom flanges *d* and *e*, respectively, and end flanges *f*, arranged substantially as shown.

Having thus described my invention, what I claim as new, and desire to secure by Letters Patent, is—

The design for an end sill for cars, substantially as herein shown and described.

In testimony whereof I have hereunto set my hand this 16th day of March, A. D. 1900.

JOHN M. HANSEN.
